United States Patent Office

Des. 209,405
Patented Nov. 28, 1967

209,405

CONFERENCE TABLE

Bernard F. Barcio, 7802 N. College Ave.,
Indianapolis, Ind. 46240

Filed Oct. 26, 1966, Ser. No. 4,435

Term of patent 14 years

(Cl. D33—14)

Fig. 1.

Fig. 2.

Fig. 3.

FIG. 1 is a top plan view of a conference table showing my design.

FIG. 2 is a front elevational view.

FIG. 3 is a left side elevational view.

The backs of the two pedestal members and the undislosed inner faces thereof are plain and unornamented.

I claim:

The ornamental design for a conference table, as shown and described.
